UNITED STATES PATENT OFFICE.

CLAUDE F. PERKINS, OF SIOUX CITY, IOWA.

PEN-WIPER.

No. 826,270.

Specification of Letters Patent.

Patented July 17, 1906.

Application filed September 23, 1905. Serial No. 279,793.

To all whom it may concern:

Be it known that I, CLAUDE F. PERKINS, a citizen of the United States, residing at Sioux City, in the county of Woodbury and State 5 of Iowa, have invented a new and useful Improvement in Pen-Wipers; and I do declare the following to be a full, clear, and exact description of the same, reference being had to the accompanying drawings, forming a part thereof.

My invention relates to means for cleaning or wiping pens, and has for its object the production of a cleaner so adjusted to the pen rack or tray that when the penholder is deposited upon the rack the pen will, if desired, come in contact with the cleaner and the ink be removed or absorbed.

I accomplish this object by means of the device shown in the accompanying drawings, 20 in which—

Figure 1 is a view in side elevation of pen-rack with wiper attached. Fig. 2 is a plan view, and Fig. 3 an end view, of same. Fig. 4 is an end view of rack, showing means of adjusting the wiper at different heights. Fig. 25 5 is a section of rack, showing means of attaching the wiper to any style of rack. Fig. 6 is a plan view of Fig. 5.

Referring now to these illustrations, in 30 which like parts are designated by similar letters of reference, A is the body or base of rack, having the usual uprights B B for the support of the penholder and pen. At one end of the base is secured a third upright C of somewhat less height than the other uprights, and to this upright is secured at the upper end a disk D by means of a thumb-screw E passing through the center of the disk and through the upper end of the upright and secured 35 therein by a nut F. The edges of the disk are furrowed to more perfectly fit the pen, and the disk is adjusted at such distance from the adjacent upright B that when the penholder is laid upon the rack the pen proper will naturally fall upon the disk. The 40 disk is also adjusted so that its upper edge extends somewhat above the level of the parts of the rack on which the holder is placed.

It will be seen that the same movement of the hand which places the pen upon the rack or tray adjusts it to the pen wiper or disk, which being of absorbent material quickly takes up the ink. If desired not to wipe the 45 pen, it may with equal facility be placed far enough toward the opposite end of the tray

to avoid the wiper. The disk freely turns upon the thumb-screw, and when one part of the absorbent material has taken all the ink it can absorb the disk is turned until all parts 60 of the edge are used, when it can be replaced with another.

In Fig. 4 is shown an upright C', having a slot c in the center composed of annular perforations which communicate with each 65 other. It provides means for regulating the height of the disk, as desired, by adjusting the thumb-screw in different parts of the slot.

My invention may be applied to any form of pen rack or tray by means of the device 70 shown in Figs. 5 and 6. The thumb-screw E', serving as an axis for the disk, passes through the lower parts of a clamp G, which in the form of a bow is bent up and adapted to fit over an upright B, a part of the original 75 rack. The axis has screw-threads on the inner end to fit the threads in the clamp, and on the opposite side of the clamp is another thumb-screw E'', also provided with screw-threads in the same way. By turning the 80 two thumb-screws the clamp may be adjusted to the upright of any pen-rack either at the top, as shown in the drawings, or on the side, and by slight modification is adjustable to any form of tray. The clamp 85 being extended outward and bent places the disk at the same distance from the upright, as shown in the other views, and sustains it in this position. The clamp has a part cut out on the upper surface, as seen in Fig. 6, to render it more easily adjustable to the upright 90 between the usual points of which the pen is placed.

The method of attaching the wiper to the rack or tray is not material to the invention; 95 neither is the form of wiper or the material of which it is composed, the essential feature of the invention being a pen-wiper adjustably secured to a pen rack or tray in such manner that when the penholder is placed in 100 the rack the pen proper will come in contact with the wiper, of which all parts may be utilized.

Having described my invention, what I 105 claim as new, and desire to secure by Letters Patent of the United States, is—

1. The combination with a pen-rack having the usual supports for a penholder, of a pen-wiper removably secured to one end of the rack at or near the height of the penholder supports, and adapted to receive or 110 come in contact with the pen proper when

the holder and pen are placed in the rack, substantially as described.

2. The combination with a pen-rack and the usual uprights thereto, of a disk of absorbent material removably secured to one end of the rack and adapted to come in contact with the pen proper when placed in the rack, means for adjusting the height of the disk with reference to said rack, and means for permitting said disk to turn thereon, substantially as described.

3. The combination with a pen rack or tray, of a disk of absorbent material removably secured thereto and adapted to come in contact with and support a pen when placed in the rack or tray, means for regulating the height of the disk with reference to said rack

or tray, and means for adjusting and securing the disk thereto, substantially as described.

4. The combination with a pen rack or tray of a disk of absorbent material removably secured thereto, a thumb-screw as an axis for said disk, a clamp having an opening and screw-threads therein for the adjustment of said thumb-screw, to secure said disk to the rack, substantially as described.

In witnesses whereof I have affixed my signature in the presence of two witnesses.

CLAUDE F. PERKINS.
